(57) **CLAIM**

The ornamental design for a record player, as shown and described.

DESCRIPTION

FIG. 1 is a front perspective view of a first embodiment of a record player, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the encircled portion of the record player labeled 8 in FIG. 1;

FIG. 9 is a front perspective view of a second embodiment of the record player, showing my new design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is a front perspective view of a third embodiment of the record player, showing my new design;

FIG. 17 is a front view thereof;

FIG. 18 is a rear view thereof;

FIG. 19 is a left side view thereof;

FIG. 20 is a right side view thereof;

FIG. 21 is a top view thereof;

FIG. 22 is a bottom view thereof;

FIG. 23 is a front perspective view of a fourth embodiment of the record player, showing my new design;

FIG. 24 is a front view thereof;

FIG. 25 is a rear view thereof;

FIG. 26 is a left side view thereof;

FIG. 27 is a right side view thereof;

FIG. 28 is a top view thereof;

FIG. 29 is a bottom view thereof;

FIG. 30 is a front perspective view of a fifth embodiment of the record player, showing my new design;

(Continued)

FIG. 31 is a front view thereof;
 FIG. 32 is a rear view thereof;
 FIG. 33 is a left side view thereof;
 FIG. 34 is a right side view thereof;
 FIG. 35 is a top view thereof; and,
 FIG. 36 is a bottom view thereof.

The broken lines shown in FIGS. 1 and 8 encircling portions illustrated in enlargements form no part of the claimed design. All other broken lines shown in the drawings illustrate portions of the record player that form no part of the claimed design.

1 Claim, 36 Drawing Sheets
